Inventor,
Merritt A. Davis
H. Seymour & C. Nichols
Attest.

UNITED STATES PATENT OFFICE.

MINOTT A. DAVIS, OF HAMDEN, CONNECTICUT.

POSITION MARKER FOR GOLF BALLS.

Application filed September 25, 1928. Serial No. 308,188.

This invention relates to an improvement in position-markers for golf balls. In playing golf it often happens that one player is stymied by the ball of his opponent. In such cases it is customary for the opponent to move his ball so as to permit the other player to putt his ball to the hole without hitting the opponent's ball. It is, of course, desirable that when the moved ball is replaced, it shall be to the same position from which it was first moved.

The object of this invention is to provide a simple device which may be inserted into the green at the point where the ball is removed. It is necessary, however, that any device used shall be of such a character as not to retard or deflect the ball being played, and the invention consists in the construction as herein-after described and particularly recited in the claims.

In the accompanying drawings:

Fig. 1 is a side view of a position-marker for golf balls constructed in accordance with my invention;

Fig. 2 is a top view of the same;

Fig. 3 is a side view of the peg detached;

Fig. 4 is a face view of the same;

Fig. 5 is a plan view of the flexible marker detached;

Fig. 6 is a front view of a modified form of peg for the position-marker;

Fig. 7 is a reverse view thereof; and

Fig. 8 is an edge view showing the peg in section.

In carrying out my invention I employ a peg 10 formed from wood or other suitable material with a narrow vertical slot 11 in its upper end into which may be inserted and fixed a strip 12 of paper or light fabric. When a ball is removed one of these devices is inserted into the green at the resting-place of the ball and pressed into the ground so that its upper end is flush with or below the

surface. The flexible strip will then lie upon the surface of the ground but will not obstruct or deflect a ball passing over it. The strip of paper or fabric may be printed with advertising matter and so adapted for this purpose, as well as performing its function as a position-marker for golf balls. After the play, the device may be readily removed and used when the next occasion requires, but if left in the ground will not form an obstruction.

As shown in Figs. 1, 2, 3 and 4 of the drawings, the device is formed in the shape of a cone and may be made from wood or any other suitable material. Instead of forming the device conical, it may be formed from sheet-metal, as shown in Figs. 6, 7 and 8 of the drawings, in which a strip of metal of suitable width is doubled upon itself to form two plates 13 and 14, the edges of the plates being tapered and one provided with a tongue 15 to pass through a slot 16 in the other member and be turned down to clamp the flexible strip 12 in place.

These devices are very small, the drawings for the sake of illustration being made on a much enlarged scale.

I claim:

1. A position-marker for golf balls consisting of a peg and a strip of tape-like material secured to the upper end thereof and projecting substantially horizontally therefrom.

2. A position-marker for golf balls consisting of a peg formed at its upper end with a vertically-arranged slot and a strip of flexible material secured therein.

3. A position-marker for golf balls consisting of a conical peg formed with a vertical slot in its upper end and a strip of flexible material secured therein.

In testimony whereof, I have signed this specification.

MINOTT A. DAVIS.
